UNITED STATES PATENT OFFICE.

MABEL GOGER, OF SAN FRANCISCO, CALIFORNIA.

SANITARY AND PROTECTIVE CAP.

1,304,960.

Specification of Letters Patent. Patented May 27, 1919.

Application filed June 26, 1914. Serial No. 847,442.

To all whom it may concern:

Be it known that I, MABEL GOGER, citizen of the United States, residing in the city and county of San Francisco, State of California, have invented certain new and useful Improvements in Sanitary and Protective Caps, whereof the following is a specification.

This invention relates to means for protecting men's, women's and children's hair and scalp while trying on hats. There are a great number of people whose heads are affected with dandruff, sores, itching scalp and kindred complaints, and at the present time there is absolutely no way of protecting one's hair and scalp from such disease while trying on hats under the present condition. When a woman tries on a hat now she runs the risk of catching all sorts of scalp diseases, as hundreds of women may have tried on the same hat ahead of her.

My sanitary cap acts as a perfect protection to the hair and scalp by preventing the head from coming in contact with the hat.

The cap also acts as a protection to the hats by preventing them getting soiled while being tried on.

Hence the invention performs a double function, namely, protecting the wearer or tryer-on and also the hat, and is therefore a sanitary article of great utility, both by itself and in combination with a hat.

In carrying out the invention I cut a disk of paper, usually circular in form, or approximately so, crimp or knife-plait its edges, so that it may be fitted over the head and hair of a lady or into the crown of a lady's hat.

Hence I call the device a "try-on cap" and its shape conforms closely to the shape of the head.

The crimp, or knife-plait's annular edge permits fitting any head by plaits opening and closing in and lying flat against the head as hat is put on.

This disk may be paraffined and perfumed to make it moisture-proof and attractive. I have found numerous essential oils satisfactory for this purpose. For example, the oil of geranium may be mixed with the paraffin and the paraffin applied in the usual way of making paraffined paper.

The sanitary cap thus produced is dis-

carded, that is, thrown away after once being used.

In the accompanying one sheet of drawings I have illustrated the invention and the mode of its use.

Figure 1 represents a lady's head, with a hat and my invention applied.

Fig. 2 is a perspective view showing the outside of my sanitary cap.

Fig. 3 is a similar view showing the interior of the same.

In these figures:

1 is a lady's head and 2 her hair.

3 is a hat which she is trying on, to determine its fit and becomingness, or any other of the many questions which arise in a lady's mind on such an occasion.

4 is the sanitary and protective cap which is placed upon the lady's head before the hat, 3, is put thereon, thereby protecting the hair and head of wearer from coming in contact with the hat, thereby preventing contagion of scalp disease and any disagreeable features arising from previous tryings-on.

The cap, 4, is composed of a paper disk which comprises the solid central portion, 5, and the knife-plaited annular portion, 6. The central portion is shown as curved so that it can adapt itself substantially to the configuration of the coiffure of the user, and the annular portion 6 may be termed an extended skirt since it has for its function to bend out over the knot of hair of the user or to extend down over the side hair even though the side hair is puffed. It may be used plain without further treatment or it may be paraffined and perfumed, as suggested hereinabove.

Having thus described my invention and an embodiment of it, in the full, clear and exact terms required by law, and knowing that it comprises novel, useful and valuable improvements in the art to which it pertains, I here state that I do not wish to be limited to the precise construction and arrangement of the several parts, as herein set forth, as the same may be variously modified by a skilled mechanic without departing from the spirit of the invention.

What I claim and desire to secure by Letters Patent of the United States is the following, to wit:

A new article of manufacture consisting

of a protective covering for the head of a person trying on hats comprising a body with a curved central portion and an extended apron adapted to bend over the hair
5 of a user to protect said hair, and plaited to expand to adapt itself to varying dimensions and configurations.

In testimony that I claim the foregoing

I have hereto set my hand in the presence of two witnesses, this 20th day of June, 10
1914.

MABEL GOGER.
